UNITED STATES PATENT OFFICE.

WILLIAM HAAS, OF WEST HOBOKEN, NEW JERSEY.

COMBINED IRONING-BOARD STAND AND WINDOW JACK OR SEAT.

Application filed February 24, 1922. Serial No. 538,878.

To all whom it may concern:

Be it known that I, WILLIAM HAAS, a citizen of the United States, residing at West Hoboken, in the county of Hudson and State of New Jersey, have invented certain new and useful Improvements in a Combined Ironing-Board Stand and Window Jack or Seat; and I do hereby declare the following to be a full, clear, and exact 10 description of the invention, such as will enable others skilled in the art to which it appertains to make and use the same.

The primary object of this invention is the provision of an article which may be used as a stand or support and as a window jack or seat, the device being of such construction as to be readily convertible from one form to the other as occasion may require and which, when not required 20 for service, may be reduced to compact form for convenience of handling and storage so as to be out of the way and not occupy valuable space.

A further purpose of the invention is the provision of a device of the nature aforesaid which is light, durable and strong and which comprises a few number of parts and is simple and economical in structure and capable of being easily and quickly 30 converted from one form to the other or reduced to a compact form for storage.

Other objects and advantages will be apparent and suggest themselves as the nature of the invention is understood.

While the drawings illustrate an embodiment of the invention it is to be understood that in adapting the same to meet different conditions and requirements, various changes in the form, proportion and 40 minor details of construction may be resorted to without departing from the nature of the invention.

Referring to the accompanying drawings forming a part of the application,

Figure 1 is a perspective view of the device in its adaptation for use as a stand or support for an ironing board.

Figure 2 is a perspective view of the device as adapted for use as a window jack 50 or seat.

Figure 3 is a detail view of the device as applied to the sill of a window of a brick structure.

Figure 4 is a transverse section of the 55 device, parts being broken away,

Figure 5 is a detail view in perspective of the lower section of the support.

Figure 6 is a fragmentary view in perspective of the upper section of the support.

Figure 7 is a detail view partly in section 60 showing respective means for connecting the support with the base or platform in different uses of the device, and

Figure 8 is a detail section of the lower frame of the adjustable support showing 65 the position of the stop member.

Figure 9 is a detail perspective view.

Corresponding and like parts are referred to in the following description and designated in the several views of the drawings by like reference characters.

The device comprises a base and a sectional support, the latter being shiftable and adapted to be secured to the base in either one of its adjusted positions. The 75 base comprises a platform 1, side elements 2 and legs 3 and 4. In the preferable construction, the platform 1 consists of sheet metal of suitable gage having opposite longitudinal edge portions bent in the same 80 direction substantially at a right angle to provide the side elements 2 which serve to stiffen and reinforce the platform. The legs 3 preferably form a part of the platform and their upper portions are deflected outwardly or crimped, as indicated at 5, to fit about the nosing 6 of a window sill. The legs 4 may be provided in any manner and attached to the base in any 85 preferred way. The side elements 2 are notched in their lower edges, as indicated at 7, and are provided with openings 8 and 9, the openings 8 being in line with the notches 7 and the openings 9 adjacent the legs 4. The legs 3 and 4 are substantially 90 of uniform length to support the platform 1 in horizontal position. A transverse strip 10, preferably of wood, is secured to the under side of the platform 1 and constitutes 95 a rest to support the same upon the sill of a wooden structure, as indicated most clearly in Figure 2. When the device is in use as a window jack or seat and is applied to the sill of a brick structure, as indicated most clearly in Figure 3, the legs 4 rest upon 100 the sill and support the outer end of the platform.

The support comprises adjustable sections designated by the numerals 10' and 11, respectively, the lower section 10 being se- 110

cured to the base and the upper section 11 being adjustable on the section 10'. As shown most clearly in Figure 5, the lower section 10' consists of a rectangular frame 5 of channel iron, the vertical members having openings 12 adjacent their lower ends, stops 13 intermediate their ends and keepers 14 at their upper ends. The lower member of the section 10' is adapted to be disposed beneath the platform 1 and enter the notches 7 or engage the lower edges of the elements 2 adjacent the legs 4, according to the position of the support and the adaptation of the device for use either as a jack 15 or stand. The upper section 11 is slideable vertically in the upright side members of the section 10 and when elevated is supported by means of stops 13, entering notches 15 in the ends of the side members of the 20 section 11, as indicated most clearly in Figure 1, and when lowered is prevented from displacement by the stops 13 engaging openings 15' formed in the side members thereof. A bolt 16 secures the part 10' 25 to the base in either position. When the part 10' is in the position indicated in Figure 1, the bolt 16 passes through the registering openings 8 and 12. When the part 10' is in the position indicated in 30 Figure 2, it is retained in place by means of the bolt 16 passing through the registering openings 12 and 9. The cross member of the section 11 is depressed to form a rest for an end of an ironing board and prevent 35 lateral displacement thereof, the opposite end of the ironing board being supported in any usual or preferred way.

When the device is adapted for use as a stand or support for an ironing board or 40 the like, the frame 10' is attached to the base approximately at a central point and occupies a vertical position, as indicated most clearly in Figure 1. This provides a substantial support which is not liable to 45 tilt because of the central position of the parts 10' and 11. When the device is adapted for use as a window jack or seat, the frame 11 is telescoped in the frame 10' and the latter occupies a position at one end 50 of the base, as indicated most clearly in Figures 2 and 3. In this position of the frame 10', it inclines to form a convenient rest for the back and the platform 1 constitutes a seat. The crimped portions 5 of the legs 3 engage the nosing 6 of the window 55 sill and prevent outward displacement of the device. When the jack is applied to the sill of a wooden structure, the transverse strip 10 rests upon the sill as indicated most 60 clearly in Figure 2. However, when the jack is applied to the sill of a brick or other structure of masonry, the legs 4 rest upon the sill, as indicated most clearly in Figure 3. When the device is not required 65 for immediate use, the frame 10' may be

detached from the base and placed thereon, thereby reducing the article to compact form so as to occupy a minimum amount of space.

The normal tendency of the arm of the frame 11 is to move toward each other, the frame being constructed of resilient metal the arms may be spread in order that the openings 15' will receive the lugs 13. When it is desired to disengage the arms of the frame from the lugs 13, it is but necessary to insert a sharpened instrument or an instrument having a relatively sharp edge, under the lower ends of the side arms of the frame 11, and the side arms may be pried outward 80 from the side arms of the frame 10' and the lugs 13 released from the notches 15'. A slight upward movement of the arms 11 will then permit the frame to be drawn upward 85 to bring the notches at its lower end into engagement with the lugs 13 and the frame will be supported in elevated position.

What is claimed is:

1. In a device of the character specified, telescoping sections, one of the sections having its side members channeled and provided at one end with keepers and having intermediate stops and the telescoping section being slideable in the channels and retained in place by means of the keepers and held 95 in extended or closed position by means of the said stops.

2. A device of the character specified comprising a base including depending reinforcing elements at opposite longitudinal 100 edges, said reinforcing elements having notches in their lower edges and provided with intermediate and terminal openings, the intermediate openings being in line with the notches transversely of the base, a support comprising a transverse member and side members, the transverse member adapted to extend beneath the base and enter the notches of the reinforcing elements 105 or engage the lower edges thereof, the lower ends of the side members having openings to register with the openings of said reinforcing elements in either position of the support, and a bolt adapted to pass through the registering openings and secure the support in either adjusted position.

3. A combined stand and window jack comprising a base, supporting means for said base, said means being adapted to secure the base to a window sill when the device is to be used as a window jack and adapted to support the base on the floor when used as a stand, and a support extending vertically above the base and shiftable thereon from an intermediate to a 115 terminal position.

4. A combined stand and window jack comprising a base, supporting means for said base, said means being adapted to secure the base to a window sill when the 130

device is to be used as a window jack and adapted to support the base on the floor when used as a stand, and a support extending vertically above the base and shiftable thereon from an intermediate to a terminal position, and means for securing the support to the base in either of its positions.

In testimony whereof I affix my signature in presence of two witnesses.

WILLIAM HAAS.
